UNITED STATES PATENT OFFICE.

VICTOR FREISINGER, OF ATLANTIC CITY, NEW JERSEY.

DESIGN FOR A CUP.

SPECIFICATION forming part of Design No. 34,781, dated July 16, 1901.

Application filed June 19, 1901. Serial No. 65,207. Term of patent 7 years.

To all whom it may concern:

Be it known that I, VICTOR FREISINGER, a citizen of the United States, and a resident of Atlantic City, in the county of Atlantic and State of New Jersey, have invented and produced a new and original Design for Cups, of which the following is a specification, reference being had to the accompanying drawings, forming part thereof, in which—

10 Figure 1 is a perspective view of my cup; and Figs. 2, 3, and 4 are side elevations of the same, showing the cup from different points.

As shown in the aforesaid drawings, my design consists of a cup having sea-scenes A and B and ornamental scrollwork C, suggestive of the seashore, which is formed partly of

shells, star-fish, lobsters, and turtles, which scrollwork divides the exterior surface of the cup into panels containing pictorial representations.

Having described my invention, what I claim as new, and desire to secure by Letters Patent, is—

The design for a cup, as herein shown and described.

In testimony whereof I hereby sign my name to this application, in the presence of two subscribing witnesses, this 10th day of June, 1901.

VICTOR FREISINGER.
